UNITED STATES PATENT OFFICE

PLINY N. JOSLIN, OF DE KALB, ILLINOIS

ROLLER SKATE

Application filed October 8, 1927. Serial No. 224,879.

My invention relates to roller skates, and among the objects thereof are to provide a construction which will permit a maximum range of adjustment between short and long sizes or lengths to fit the shoes of different skaters; to provide a skate of rigid and durable construction which may be economically produced in quantities; to provide a novel construction in which the heel plate and shank 10 girder, as well as the rear flange of the heel plate are made in one piece, thereby permitting the same to be stamped in a single blank with a cutting die and formed into proper shape in a simple manner to give extraordinary strength and resistance to sag or looseness at the shank; to provide a shank girder of inverted channel or U-shaped cross-section so as to present a much neater and finished 15 appearance and give better bracing effect, as well as prevent exposure of the edges of the shank; to provide novel truss supports and truck hangers for the front and rear or heel and toe or foot plates and wheels thereof, which may be produced from novel blanks formed 20 from the same stamping and forming dies for either rigid or oscillating cushion trucks for the wheels, thus economizing in manufacturing costs; to so construct the front hangers as to frictionally receive the shank girder 25 for sliding adjustment between the same and the toe plate, as well as to avoid play therebetween, and to provide means for rigidly clamping said parts together, whereby they will positively remain fixed in any adjusted 30 position.

Other objects and advantages of the invention will be understood by reference to the following specification when considered in connection with the accompanying drawing, 40 in which:—

Fig. 1 is a side elevation of one form of 45 skate construction in accordance with the invention.

Fig. 2 is a vertical section taken on the section line 2—2 of Figure 1.

Fig. 3 is a perspective view of a heel plate with integral rear flange and shank girder.

Fig. 4 is a perspective view of one of the 50 truck hangers, modified for use in conjunction

with the toe plate of the skate and to receive and brace the shank girder.

Fig. 5 is a plan view of a blank from which the truck hanger shown in Figure 4 is formed.

Fig. 6 is a side elevation partly broken away 55 and in section of another form of skate constructed in accordance with the invention and employing oscillating cushion trucks adapted to permit of the cushioning of the wheels and the tilting of the trucks transversely of the skate.

Fig. 7 is a fragmentary plan view of the combined heel plate, rear flange, and shank girder with the latter broken away.

Fig. 8 is a vertical sectional view taken on 65 the section line 8—8 of Figure 6.

Fig. 9 is a sectional view taken on the section line 9—9 of Figure 6.

Fig. 10 is a side elevation of a truss hanger employed in the construction shown in Figure 6.

Fig. 11 is an end elevation of the truck hanger shown in Figure 10, and

Fig. 12 is a plan view of a blank from which the truck hanger shown in Figures 10 and 11 75 is produced.

Referring to the drawings in detail and especially to the constructions shown in Figures 1 to 5 inclusive in which the skate is illustrated as being of that type having rigid 80 truck hangers, 13 designates the heel plate which is produced from a single blank of metal stamped from a sheet so as to produce a combined heel plate, rear flange, and shank girder, the rear flange being designated at 14 and the shank girder at 15. The heel plate 13 has its side edges turned downwardly to produce stiffening flanges 16 and the rear flange 14 is bent upwardly with a slight rearward inclination and is curved to conform to the rear edge of the plate 13 and the heel which it is adapted to fit. The result is a flange of concavo-convex formation with a convex top edge 17 and front edges 18 which are convexly rounded and slope downwardly and rearwardly to doubled lower side portions 19 below the plane of the heel plate 13 and which approach the plane of the plate in an upward curve rearwardly at each side.

These doubled portions 19, as before stated, depend below the plane of the heel plate 13 with resultant inside depressions or grooves 20 which form continuations of the depending side flanges 16 of the heel plate, or from which these flanges are generated so as to reinforce and stiffen the heel plate as well as to avoid exposed edges. The flanges 16 also preferably incline slightly outwardly as they approach the juncture 21 with the shank girder 15, at which point the shank girder is slightly depressed to bring it in a plane beneath the toe plate 22 of the skate. The flanges 16 are continued along the sides of the shank girder 15 as indicated at 23, besides the flanges being preferably vertically disposed in parallel relation to each other so as to form a member which is narrower than the heel plate and of substantially inverted channel or U-shaped cross-section. The shank girder 15 has a longitudinal slot 24 centrally of its top portion extending the greater portion of the length thereof equi-distantly between the sides and terminating in spaced relation to the depressed portion 21 at its juncture with its heel plate and the forward extremity. The rear flange is provided with inclined slots 25 adapted to take a strap or strap sections 26 for tightening the skate around the ankle of the skater.

The toe plate 22 is equipped with the usual toe clamps 27 slidably mounted beneath the toe plate for adjustment toward and away from each other by means of an adjusting screw 28, as commonly employed. Both the heel and toe plates are provided with opposed pairs of spaced slots 29 preferably disposed equi-distantly apart and parallel to each other, four in number being preferably employed on each plate and those of the toe plate being preferably located nearer the rear end thereof than its forward end to which the toe clamps 27 are fastened.

This type of skate is equipped with rigid truck hangers 30, which are of like construction at both front and rear except for slight modification of the front truck hanger for co-operation with the shank girder 15 for permitting adjustment of the length of the skate, as will be hereinafter more particularly pointed out. These modifications consist in treatment of the blank as additional operations to those required for the stamping and formation of the rear hanger. Therefore, both hangers are of the same or duplicate construction and may be produced by the same stamping and forming dies.

As shown more particularly in Figures 4 and 5, these truck hangers are produced from a blank having an intermediate portion 31 with side extensions 32 turned to provide strap sections or axle receiving portions of substantial tubular formation shown in Figure 4, the intermediate portion of the blank

being stiffened longitudinally with a bent rib 33 which, however, terminates short of the inner ends of each hanger, as designated at 34. The blank is also provided with side extensions 35 at one end which are considerably longer than extensions 36 at the other end and which are bent at right angles to the intermediate portion after the axle-receiving or transverse bight portion 32 is formed and the intermediate parts 37 and 38 are bent upwardly at obtuse angles to each other slightly greater than a right angle. By this means, the recessed edges 39 of the side extensions 35 and 36 are brought together vertically above the axle-receiving portion 32, and the edges 40 which engage the bottom of the heel and toe plates are provided with reduced extensions or lug rivets 41 which are received in the slots 29 and upset to securely fasten the truck hangers in position.

The front and rear truck hangers are of similar construction so far as described, but they are disposed in reversed positions with the longest inclined portions produced by 90 the folding lines 42 between the portions 35 and 37 disposed innermost as compared to the folding lines 43 between the portions 36 and 38 which are disposed toward the ends of the skate. Each truck hanger receives a pin or axle 44 in its axle-receiving portion or strap section 32 in which the axle is clamped in position and wheels 45 are journaled on the axles.

The shank girder 15 extends between the sides of the front truck hanger, these sides being parallel and the truck hanger being of substantially U-shaped cross section as disclosed more particularly in Figures 2 and 4 of the drawings, the purpose of which is to permit adjustment of the length of the skate by sliding the toe plate and its hanger with respect to the heel plate and its hanger on the shank girder 15 and clamping the same in adjusted position. This construction is such as to permit a maximum range of adjustment with a very short skate, as well as a very long one, and in order to effectively brace the connection between the shank girder and the toe plate and front truck hanger, the latter is provided with shoulders 46 facing upwardly on the inside to engage the bottom edges of the flanges 23. These shoulders are shown in the form of indented portions or lugs produced in the side extensions 35 to tightly friction against the bottom edges of the flanges 23 but with sufficient looseness to permit sliding adjustment of the shank girder in the front truck hanger.

The flanges 23 also fit against the inner faces of the side walls of the truck hangers 30 produced by the extensions 35 and 36 and a central intermediate portion 47 of the part 37 is slit as at 48 and turned up to engage the bottom face of the shank girder 15 to addi- 120

tionally brace the girder and shank of the skate. A bolt 49 is disposed through an opening 50 in the toe plate 22 near its rear end and engages the slot 24 to securely clamp the parts in adjusted position. It will be seen that the front and rear truck hangers are the same except for the lugs or shoulders 46 and the upturned bracing portion 47 which are only provided on the front hanger. 10 and that these parts may be otherwise stamped and shaped from the same stamping and forming dies.

In the form shown in Figures 6 to 12 inclusive, the construction is identical with the 15 construction previously described except that the strap 51 is shown encircling the back of the rear flange 14 and, of course, both straps 26 and 51 have the usual buckle, known in the art. In lieu of the truck hangers 30, 20 truck hangers 52 are provided, the same being stamped from a single blank to provide an intermediate axle mounting or transverse bight portion 53 with depending ends 54 and having side extensions 55 branching 25 from the side edges of the intermediate part 53 and enlarged outwardly. These portions 55 are disposed in divergent relation so that when they are bent up at right angles they are disposed parallel with the top edges 30 56 horizontal. These edges have correspondingly reduced portions or lug rivets 57 which are passed through the slots 29 and upset.

The sides 55 are also offset outwardly 35 along lines parallel to the edges 56 as shown at 58 to provide stiffening means as well as to inform shoulders facing upwardly at the inside as at 59. These shoulders are designed to receive the bottom edges of the flanges 23 of the shank girder in frictional contact 40 therewith as seen more particularly in Figures 6 and 8 so as to brace the parts when connected by the bolt 49, as previously described. The portions 54 are apertured as at 60 and receive therebetween the usual 45 oscillating cushion truck supports 61 which have rubber inserts 62 and the portions 54 are connected by pins 63 to corresponding apertured upturned portions of strap sections 65, this construction being such as to 50 permit cushioning of the wheels and tilting of the trucks transversely of the skate.

The axles 64 are mounted in the strap sections or axle receiving portions 65 and take the wheels 66, which may be of metal or 55 cushion tread type. In this construction the front and rear truck girders may be produced from the same dies, although if desired the front truck may have its sides more widely spaced apart, but this is not essential. 60 In each case a skate of pleasing appearance is provided which is very strong and rigid and effectively embraced intermediately so as not to give at the joint or shank portion where the shank girder and toe plate connect. 65 While I have shown several means of ac-

complishing the objects of the invention, it is to be understood that other forms may be provided and that modifications may be resorted to in the construction and arrangement of the parts without departing from the spirit of my invention so long as the same do not depart from the scope of the device as claimed.

I claim as my invention:

1. In a roller skate, a heel plate having an 75 integral shank girder, and a toe plate, the shank girder extending under the toe plate from the rear end of the latter, and said rear end being located within the length of the girder.

2. In a roller skate, a heel plate having an 80 integral shank girder and an integral rear flange, a toe plate positioned in the plane of the heel plate, above the shank girder and terminating above the same, the shank girder 85 being adjustably secured to the toe plate, and means bracing said shank girder against the bottom of said toe plate.

3. A roller skate comprising a heel plate 90 having an integral forwardly extending shank girder with down-turned side flanges and a rear flange all formed from a single blank, an attachment means attached to the rear flange, a toe plate entirely over and adjustably connected to the shank girder with 95 its rear end positioned over the shank girder, said shank girder extending under the toe plate from the rear end thereof and being adjustably clamped to the toe plate, truck hangers carried by the heel and toe plates, and 100 rollers journaled in said hangers.

4. A skate comprising a heel plate having a rear flange, depending side flanges and a shank girder extending forwardly therefrom and having depending side flanges formed as 105 a continuation of the side flanges of the heel plate, said parts being formed from a single blank pressed into shape, a toe plate adjustable longitudinally on and entirely over the shank girder, attachment means on the rear flange and toe plate, and traction means carried by the heel and toe plates.

5. In a skate, a heel plate having a rear flange with side portions depending below 110 said plate and depending side flanges, said depending side portions being united to the side flanges, a shank extending forwardly from the heel plate and formed integral therewith, said shank having side flanges continuing from the side flanges of the heel plate to the forward end of the shank, all of said parts being formed from a single blank.

6. In a skate, a heel plate having depending side flanges, a rear flange with side portions extending below said plate, doubled and joining said side flanges, a shank extending 115 forwardly from the heel plate and formed integral therewith, said shank having side flanges continuing from the flanges of the heel plate, and having a longitudinal slot, a 120

- toe plate, fastening means near the rear end of the toe plate and slidably fitting in the slot to clamp the toe plate in longitudinally adjusted position on the shank, attaching means carried by the rear flange and toe plate, and hangers carried by the heel and toe plates.
7. In a skate, a heel plate having depending side flanges, a rear flange with side portions depending below said plate, said depending side portions being doubled and joining the side flanges on the heel plate, a shank extending forwardly from the heel plate and formed integral therewith, said shank having side flanges continuing from the flanges of the heel plate and having a longitudinal slot, a toe plate, fastening means near the rear end of the toe plate and slidably fitting in the slot to clamp the toe plate in longitudinally adjusted position on the shank, truck hangers attached to the heel and toe plates and having traction means, the hanger of the toe plate having upwardly facing side shoulders engaging the flanges of the shank to brace the shank in frictional sliding engagement with the toe plate.
8. In a skate, a heel plate having depending side flanges, a rear flange with side portions depending below said plate, said depending side portions being doubled and joining the side flanges on the heel plate, a shank extending forwardly from the heel plate and formed integral therewith, said shank having side flanges continuing from the flanges of the heel plate and having a longitudinal slot, a toe plate, fastening means near the rear end of the toe plate and slidably fitting in the slot to clamp the toe plate in longitudinally adjusted position on the shank, combined truss supports and truck hangers carried by the heel and toe plates, said hangers being substantially U-shaped cross section, each including an integrally formed bottom portion and side portions secured to the respective heel and toe plates, the toe plate receiving the shank thereunder and the front hanger having upwardly facing side shoulders engaging the bottom edges of the flanges of the shank to brace the same against the toe plate when adjusted.
10. In a skate, a heel plate having depending side flanges, a rear flange with side portions depending below said plate, said depending side portions being doubled and joining the side flanges on the heel plate, a shank extending forwardly from the heel plate and formed integral therewith, said shank having side flanges continuing from the flanges of the heel plate and having a longitudinal slot, a toe plate, fastening means near the rear end of the toe plate and slidably fitting in the slot to clamp the toe plate in longitudinally adjusted position on the shank, combined truss supports and truck hangers carried by the heel and toe plates, said hangers being substantially U-shaped cross section, each including an integrally formed bottom portion and side portions secured to the respective heel and toe plates, the toe plate receiving the shank thereunder and the front hanger having upwardly facing side shoulders engaging the bottom edges of the side flanges of the shank to brace the same against the toe plate when adjusted and the rear part of the bottom portion being turned up against the bottom face of the shank between the flanges thereof.
11. In a roller skate, a heel plate having side flanges, attachment means and a forwardly extending shank girder with depending side flanges throughout the length thereof, a foot plate adjustably connected to the shank girder, and truck hangers attached to said plates and depending therefrom.
12. In a roller skate, a heel plate having side flanges, attachment means and a forwardly extending shank girder with depending side flanges throughout the length thereof, a foot plate adjustably connected to the shank girder, truck hangers attached to said plates and depending therefrom, said truck hangers being each stamped from a single blank with angularly extending side portions having divergent edges and having axle-receiving portions, axles mounted therein, and wheels on said axles.
13. In a roller skate, a heel plate having side flanges, attachment means and a forwardly extending shank girder with depending side flanges throughout the length thereof, a foot plate adjustably connected to the shank girder, truck hangers attached to said plates and depending therefrom, said truck hangers being each stamped from a single blank with angularly extending side portions having divergent edges, the front hanger having inwardly offset portions spaced from the top edges thereof and the foot plate to engage the bottom edges of the flanges of the

shank girder and brace the same against the bottom face of the foot plate.

14. In a roller skate, a heel plate having side flanges, attachment means and a forwardly extending shank girder with depending side flanges throughout the length thereof, a foot plate adjustably connected to the shank girder, truck hangers attached to said plates and depending therefrom, said truck hangers being each stamped from a single blank with angularly extending side portions having divergent edges, the front hanger having inwardly offset portions spaced from the top edges thereof and the foot plate to engage the bottom edges of the flanges of the shank girder and brace the same against the bottom face of the foot plate, and means carried by the said hanger to engage the intermediate portion of the shank girder below the foot plate.

15. A roller skate having a foot plate, a heel plate with an integral shank slidably connected to the foot plate and having depending side flanges, and hangers carried by said plates and depending therefrom, said hangers each formed of a single blank sheet metal shaped to provide side portions with shoulders facing upwardly in engagement with the bottom edges of the side flanges of the shank and intermediate connecting portions at the bottom.

16. A roller skate having a foot plate, a heel plate with an integral shank slidably connected to the foot plate, said shank having side flanges, and hangers carried by said plates and depending therefrom, said hangers each formed of a single blank of sheet metal shaped to provide side portions and intermediate connecting portions at the bottom and the front hanger having shoulders spaced from the foot plate and parallel thereto to engage the bottom edges of the shank flanges, and attachment means carried by the heel and foot plates.

17. A roller skate having a foot plate, a heel plate with an integral shank slidably connected to the foot plate, said shank having side flanges, and hangers carried by said plates and depending therefrom, said hangers each formed of a single blank of sheet metal shaped to provide side portions and intermediate connecting portions at the bottom and the front hanger having shoulders spaced from the foot plate and parallel thereto to engage the bottom edges of the shank flanges, and an upwardly and rearwardly extending flange at the rear of the heel plate having downwardly curved front side portions doubled to form depending side flanges on the sides of the heel plate, and said side flanges terminating in said shank side flanges, the latter constituting continuations of said heel plate side flanges.

18. In a skate, a heel plate having an upwardly extending rear flange with side por-

tions depending below said plate, and depending side flanges, said depending side portions being united to said side flanges.
